UNITED STATES PATENT OFFICE.

JOHN ALONZO, OF DEBORGIA, MONTANA.

RAILWAY-SWITCH.

1,399,914.

Specification of Letters Patent. Patented Dec. 13, 1921.

Application filed May 15, 1920. Serial No. 381,725.

To all whom it may concern:

Be it known that I, JOHN ALONZO, a subject of the King of Italy, residing at Deborgia, in the county of Mineral and State of 5 Montana, have invented certain new and useful Improvements in Railway-Switches; and I do declare the following to be a full, clear, and exact description of the invention, such as will enable others skilled in the art 10 to which it appertains to make and use the same.

My invention relates to improvements in railway switches of the type in which the switch tongues are movable vertically from 15 end to end instead of having the usual pivotal movement. Switches of this general form have been heretofore devised, but my principal object is to provide more efficient means for anchoring the fixed rails, guiding 20 the switch tongues, and raising and lowering said tongues.

With the foregoing and minor objects in view, the invention resides in the novel construction and arrangement of parts hereininafter described and claimed, the descriptive matter being supplemented by the accompanying drawings.

Figures 1 and 1^a jointly illustrate a top plan view of a switch constructed in accordance with my invention.

Fig. 2 is a side elevation of a portion of the switch.

Fig. 3 is a side elevation of the parts shown at the left of Fig. 1.

Fig. 4 is a vertical transverse section on the plane indicated by line 4-4 of Fig. 1 and Fig. 5 is a similar view on the plane of line 5-5 of Fig. 1^a.

Fig. 6 is an end view of one of the boxes 40 which support the fixed rails, guide the switch tongues, and contain the raising and lowering wedges for said tongues.

Fig. 7 is a side elevation of the box shown in Fig. 6 and Fig. 8 is a top plan view 45 thereof.

Fig. 9 is an end elevation of one of the boxes shown at the left end of Fig. 1, which boxes contain the master gears used in operating the wedges.

Fig. 10 is a side elevation of the box 50 shown in Fig. 9 and Fig. 11 is a top plan view thereof.

Fig. 12 is a view similar to the left end of Fig. 2 but showing one of the wedges in 55 section and illustrating also the manner in which certain of said wedges are connected with the switch tongues.

Figs. 13 and 14 are vertical transverse sections on the planes indicated by the lines 13-13 and 14-14 of Fig. 1.

Figs. 15 and 16 are respectively a top plan view and a side elevation of an angle iron which carries a ballast retaining strip.

Fig. 17 is a plan view of one of the plates 47.

Fig. 18 is an upper edge view of one of the filler strips interposed between the switch tongues and the adjacent fixed rails.

Fig. 19 is an upper edge view of one of the switch tongues and Fig. 20 is a side elevation thereof.

Fig. 21 is a top plan view of one of the longitudinal rack bars employed for operating the wedges.

Fig. 22 is a top plan view of one end of 75 one of the line rails and the associated spacer.

Fig. 23 is a transverse section on the plane of line 23-23 of Fig. 22.

Fig. 24 is a top plan view of part of the 80 anchoring means of the line rail end shown in Fig. 22.

Fig. 25 is a detail vertical section on line 25-25 of Fig. 24.

In the drawings above briefly described, 85 the character L designates the continuous line rail while L' refers to the other line rail, a portion of the latter extending laterally to form one of the rails S' of a siding. L² refers to a line rail which receives the car 90 wheels as they travel from the straight portion of the rail L', a vertically movable switch tongue T' being used to bridge the gap between these two rails. Rail S coacts with rail S' in forming the siding, and a 95 vertically movable switch tongue T is employed to direct the car wheels onto said rail S from the rail L.

The several rails L, L' and S are rigidly supported by a plurality of metal boxes B, 100 B' and B², and all of these boxes with the exception of those indicated at B¹, serve to guide the switch tongues T and T' as well as to contain rotary wedges for raising and lowering said tongues. The wedges in the 105 boxes B are designated by the character W while those in the boxes B² are referred to by W', for sake of referring more specifically to these parts in the following description. The boxes B' contain master gears G which 110 are used to transmit motion from a transverse operating bar O to longitudinal operating bars O' which serve to actuate the wedges W and W'.

A specific description of all of the features above briefly described, follows below.

The boxes B are detailed more particularly in Figs. 5, 6, 7 and 8 and in the following specific description, reference is made to these views only, a number of reference characters being omitted from the general views to avoid confusion. A description of these boxes will apply also to 10 the boxes B² with the exception that the latter are of slightly greater size. Each of the boxes in question (see Fig. 8) comprises two sections 1 and 1' which may be secured together by means of bolts 2 passing 15 through lateral ears 3. These sections however may be separated to any required extent by separators 4 interposed between the sections 1 and 1', and the thickness of such separators depends upon the distance 20 which the rails are spaced apart on the box. Each of the separators 4 is preferably provided with lateral lugs 5 received in recesses 6 in the ends of the two sections 1 and 1', to effectively hold said separators 25 in place.

Each section 1 and 1' of the box B consists of a bottom plate 7, a pair of side walls 8 and a top plate 9, and the plate 9 of each section 1 is lacking between a pair of opposed notches 10 formed in the side walls 8, whereby to form guides to receive the switch tongue T or T'. The bottom plates 7 are provided with suitable holes 11 to receive spikes by means of which the boxes are secured to suitable ties 12, and the outer end of each section 1 is also provided with a vertically elongated spike receiving guide 13 for a purpose yet to be described. Adjacent this guide, the top plate 9 is provided with an upstanding lug 14 which contacts with the notches 10 in guiding the switch tongues. This lug however need not be provided on every box, it being usually sufficient to equip the alternate boxes with 45 this feature.

The opposed side walls 8 are provided with slots 15 through which the operating bars O' are slideable, said bars having rack teeth 16 meshing with gear teeth 17 which 50 are carried by the lower sides of the wedges W and W'. Each of the wedges W comprises a circular body 18 and a pair of opposed inclined wedge surfaces 19 upon which the switch tongue T or T' rests, and whenever the wedges stand as seen in Fig. 4, the tongue will be raised, while turning of the wedges to the position of Fig. 5, will lower the tongue.

The boxes B and B² are spaced apart 60 throughout substantially the length of the tongues T and T' as shown clearly in Figs. 1 and 1^a, and said boxes B', a detail of which is shown in Fig. 12, contain the wedges W' which differ from those above described, in 65 that they are provided with laterally ex-

tending flanges 20 having the same inclination as their inclined wedge surfaces 19'. The flange 20 of each of the wedges W' overrides a roller 21 carried by an L-shaped arm 22 which is suitably secured at 23 to 70 the base of the switch tongue T or T'. It thus follows that since the wedges cannot move vertically within their retaining boxes, the switch tongues cannot creep with respect to said wedges, nor can such tongues 75 fail to lower when the wedges are properly turned.

Any suitable means may be employed for rotatably mounting the several wedges, but I prefer that shouldered cap screws 24 80 shall be used for this purpose, said screws passing through openings in the wedges and being threaded into the base plates 7 of the boxes. If desired, these boxes may be provided with machined bosses 25 upon 85 which the wedges rest as shown for instance in Figs. 4, 5 and 12.

The boxes B' are constructed in substantially the same manner as those above described but no supporting wedges need be 90 mounted in these boxes since the ends of the switch tongues under which they are located, support no weight of the car wheels, such weight at this point being carried by the rails L and L'. Furthermore, as shown in 95 Figs. 9, 10 and 11, these boxes are provided with no tongue guiding notches, although their upper sides are preferably equipped with bosses 14' for this purpose. Where the ends of the tongues pass over the boxes 100 B', their lower sides are preferably cut away as shown in dotted lines at 26 in Fig. 3 and in full lines in Fig. 20. Each box B' is provided in one of its vertical sides with a notch 27 through which the master gear 105 G projects into proximity with a guide 28 on the side of said box for guiding the transverse operating bar O. This guide may well be of the L-shape shown in Figs. 9 and 11. The box B' is also formed with 110 slots 15' corresponding to the slots 15 to receive the longitudinal operating bars O'. The gears G may be mounted in any desired way within the boxes B', but vertical spindles 24' carried rigidly by the bottoms 115 of said boxes, are preferably employed, as detailed in Fig. 9.

The ends of the several boxes which are equipped with the lugs 14 or 14', are positioned inwardly, and angle metal plates 30 120 (Figs. 1, 1^a, 15 and 16) rest on these ends of the boxes and are notched as at 31 wherever a lug is encountered. The horizontal part of each plate 30 is secured by spikes 32 which pass through the spike guides 125 13 above described and enter the ties 12 as seen most clearly in Figs. 4 and 5. The vertical flanges of the plates 30 abut the adjacent rails, while the horizontal portions of said plates are secured by any preferred 140

means to longitudinal strips 33 which rest on the ties and extend substantially throughout the length of the switch. These strips 33 serve to retain ballast between the two 5 sets of rails at the opposite sides of the switch.

Forming continuations of the plates 30, at the ends thereof adjacent the siding S and S', are two anchor-plates 30' which 10 are shown in Figs. 1^a, 24 and 25, the horizontal flanges of these plates being spiked down at 32', while their vertical flanges carry metal bars 34 at one end, the inner ends of these bars being shouldered at 35 to engage 15 corresponding shoulders 36 on the pointed ends of the rails S and L², as shown in Fig. 1^a and 22. The shoulders 36 are also formed in part on the ends of spacing bars 37 shown in the same figures, said bars being 20 interposed between the plates 30' and the rails L² and S. The spacing bars 37 are rigidly secured to the rails by rivets or the like 38 as indicated in Fig. 22, and bolts 39 assist in securing these parts together. 25 The bolts 39 at one side of the track pass through the upstanding flange of the plate 30', through the spacing bar 37, through the rails S and L, and through a spacing block 40 located between these rails as seen 30 in Fig. 1^a. The bolts 39 at the opposite side of the track however pass through the rails L' and L², through a spacing block 40' between them, through the spacing bar 37 and the upstanding flange of the plate 30'. 35 This is shown in Fig. 1^a, Fig. 22, and in Fig. 23.

Extending from the spacing blocks 40 and 40' to the opposite ends of the switch, are a pair of spacers 41 and 41', these spacers 40 being shown in several of the sectional views and in Figs. 1 and 1^a. Furthermore, a detail of the spacer 41' is shown in Fig. 18. The spacer 41 is located between the tongue T and the rail L to assist in guiding the 45 former and to prevent tilting thereof, while the spacer 41' is located between the rail L' and the tongue T' and performs a similar function on the latter. The shoulders 35 and 36 above described prevent the thinned ends 50 of the rails S and L² from being crowded over against the tongues T and T' and binding the latter tightly against the spacers 41, so that said tongues are free to move vertically whenever necessary. Preferably, the 55 plates 30' which carry the shoulders 35, are equipped with strips 33' forming continuations of the strips 30 and serving the same purpose as the latter.

The line rails L and L' could be anchored 60 upon the several boxes in any suitable manner, but the details shown are preferably followed. Suitable rail braces and anchors 45 are secured by bolts or the like 46 to the top plates of the box sections 1', and longitudinal plates 47 are preferably inter-

posed between such boxes and anchors as shown.

The switch tongues T and T', reference being now made solely to Fig. 9, are straight between the lines 48, while the opposite ends 70 of said tongues turn obliquely in opposite directions as indicated at 49, and in order that the several supporting wedges of these tongues may be positioned substantially under the centers of the latter, I construct the 75 operating bars O' of the same general shape as the switch tongues, as seen clearly in Fig. 21. In order that this may be successfully accomplished and that the teeth 16 for each of the wedges shall move on parallel lines 80 when the bar is shifted, I construct this bar of stepped form, preferably employing a plurality of short sections 50 secured together by rivets or the like 51.

When the bar O is operated to raise the 85 switch tongue T, the tongue T' is correspondingly lowered, with the result that a train approaching in the direction of the arrow of Fig. 1, will travel from the track L along the raised tongue T onto the siding rail S, and along the rail L' to the siding rail S'. When tongue T' is raised however, tongue T is correspondingly lowered with the result that the train continues on the main line, a part of which is now formed 95 by said tongue T'.

The construction employed is of great advantage in that it effectively anchors all of the rails, guides the switch tongues, and forcibly raises or lowers such tongues uniformly throughout their lengths. Furthermore, the form of switch disclosed is not prone to clog with snow and ice as is the case with the ordinary pivoted tongue switches. The boxes B, B' and B² are made 100 as small as possible to admit only an infinitesimal amount of ice or dirt and hence the moving parts therein will not be jammed. Also, these parts are protected by the boxes and the several plates above described. 105 The flanges 20 on the wedges W' not only forcibly lower the switch tongues, but they prevent any longitudinal movement of such tongues. There are fewer parts employed than in most switches of the general type 110 disclosed and the switch operating parts are substantially on the same level with the track, in actual practice, the switch supporting ties being only four inches lower than the other ties. The several filler blocks 115 and strips serve to rigidly brace the rails and any bolts or rivets passing through these parts tie them tightly together to greatly strengthen the same.

On account of the existing advantages, I 125 prefer to employ the several details shown and described, but within the scope of the invention as claimed, numerous changes in form, proportion and other details may well be made.

I claim:

1. A railway switch comprising a switch tongue movable vertically throughout its length, a plurality of horizontal rotary 5 wedges supporting said tongue and mounted on vertical axes, and means for simultaneously turning all of said wedges.

2. A railway switch comprising a switch tongue movable vertically throughout its 10 length, a plurality of horizontal rotary wedges supporting said tongue and mounted on vertical axes, gear teeth on said wedges, a longitudinal rack bar meshing with the teeth on all wedges, and means for sliding 15 said rack bar.

3. A railway switch comprising a tongue movable vertically throughout its length, said tongue having its ends out of line with its central portion, a plurality of horizontal 20 wedges supporting said tongue and mounted on vertical axes, said wedges being positioned substantially beneath the center of the tongue and being therefore out of longitudinal alignment, said wedges having 25 gear teeth, and a longitudinal rack bar meshing with said gear teeth, said rack bar being stepped for proper engagement with the gear teeth and having its individual steps disposed on parallel lines.

30 4. A structure as specified in claim 3, the steps of said rack bar being formed of separate sections, said sections being rigidly secured together.

35 5. A switch comprising a pair of switch tongues movable vertically throughout their lengths, two series of horizontal wedges supporting said switch tongues and mounted on vertical axes, said wedges having gear teeth, master gears mounted at the ends of said series of wedges, a pair of longitudinal rack bars meshing with said master gears and with the teeth of said wedges, a transverse rack bar meshing also with said master gears, and guiding means for said rack bars.

40 6. A switch comprising a switch tongue movable vertically throughout its length, a plurality of boxes supporting the adjacent switch rails and having means for guiding said tongue, means within said boxes for raising and lowering said tongue, and means for operating all of said raising and 45 lowering means in unison.

50 7. A switch comprising a switch tongue movable vertically throughout its length, a plurality of boxes supporting the adjacent rails and having means for guiding said tongue, a plurality of horizontal wedges mounted in said boxes on vertical axes for raising and lowering said tongue, 55 and means for simultaneously turning all of said wedges.

8. A switch comprising a switch tongue movable vertically throughout its length, a plurality of boxes supporting the adjacent 60 rails and having means for guiding said

tongue, a plurality of horizontal wedges mounted in said boxes on vertical axes for raising and lowering said tongue, said wedges having gear teeth, and a longitudinal rack bar meshing with said teeth for turning said wedges, said boxes having means for guiding said rack bar.

70 9. A switch comprising a switch tongue movable vertically throughout its length, a plurality of boxes supporting the adjacent switch rails and having openings leading through their upper sides for guiding said tongue, opposite vertical sides of said boxes having slots, a longitudinal rack bar passing through said slots and extending across the 75 boxes, and a plurality of horizontal wedges mounted in said boxes on vertical axes for raising and lowering said tongue, said wedges having gear teeth meshing with the teeth of said rack bar.

80 10. A switch comprising a switch tongue movable vertically throughout its length, a plurality of boxes supporting the adjacent switch rails and having means for guiding said tongue, said boxes being extensible in 85 length according to the increasing distance between the rails, means within said boxes for raising and lowering the switch tongue, and means for simultaneously actuating all of said raising and lowering means.

90 11. A switch comprising a switch tongue movable vertically throughout its length, a plurality of boxes supporting the adjacent switch rails and having means for guiding said tongue, said boxes being composed of sections separable according to the increasing distance between the rails, means for rigidly securing said sections in adjusted position, means within said boxes for operating the switch tongue, and means for simultaneously actuating all of said tongue operating means.

100 12. A switch comprising a switch tongue movable vertically throughout its length, a plurality of boxes supporting the adjacent switch rails and having means for guiding said tongue, said boxes being composed of sections separable according to the increasing distance between the rails, separators adapted to be interposed between said 105 box sections, means for securing said sections and separators tightly together, means in said boxes for operating the switch tongue, and means for simultaneously actuating all of said tongue operating means.

110 13. A structure as specified in claim 12, said box sections and separators having interfitting lugs and recesses to hold said separators in place.

120 14. A switch comprising a switch tongue movable vertically throughout its length, a plurality of horizontal wedges supporting said tongue and mounted on vertical axes, means for simultaneously rotating said wedges, and connections between certain of 130

said wedges and said tongue for positively lowering the latter.

15. A switch comprising a switch tongue movable vertically throughout its length, a plurality of horizontal wedges supporting said tongue and mounted on vertical axes, means for simultaneously rotating said wedges, and connections between certain of said wedges and said tongue for positively lowering the latter and for holding said tongue against longitudinal shifting.

16. A switch comprising a switch tongue movable vertically throughout its length, a plurality of horizontal wedges supporting said tongue and mounted on vertical axes, means for simultaneously turning all of said wedges, flanges on certain of said wedges following the lines of their wedge surfaces, and means on the switch tongue engaging 20 said flanges for positively lowering the switch tongue.

17. A switch comprising a switch tongue movable vertically throughout its length, a plurality of horizontal wedges supporting 25 said tongue and mounted on vertical axes, means for simultaneously turning all of said wedges, flanges on certain of said wedges, following the lines of their wedge surfaces, and L-shaped arms depending from the 30 switch tongue and having rollers underlying said flanges to positively lower the tongue.

18. A switch comprising a switch tongue movable vertically throughout its length, a plurality of boxes supporting the adjacent 35 switch rails and having means for guiding said tongue, horizontal wedges mounted in said boxes on vertical axes for operating said tongue, said wedges having gear teeth, a longitudinal rack bar extending across the 40 several boxes and in mesh with the gear teeth of said wedges, an additional rail supporting box at one end of the switch, a master gear mounted in said additional box and projecting through an opening in the 45 side thereof, said master gear meshing with said longitudinal rack bar, a transverse rack bar meshing also with said master gear, and guiding means for said transverse rack bar carried by said additional box.

50. 19. A switch including a vertically movable switch tongue having an oblique end, a rail having a tapered end overlapping said switch tongue end, an anchor rigidly secured to the supporting structure of the rail-way, and abutting shoulders on said anchor and said tapered rail to prevent the latter from crowding against and binding said tongue end.

20. A switch including a vertically movable switch tongue having an oblique end, a rail having a tapered end overlapping said tongue end, a longitudinal plate rigidly secured to the supporting structure of the rail-way and having an upstanding flange, a bar

secured to said flange and interposed between one end of the latter and said tongue, said bar having a shoulder on its inner end, and a spacing bar secured between said flange and said tapered rail end, said spacing bar and said rail end being shouldered to 70 coact with the aforesaid shoulder for preventing crowding of the switch tongue by said rail end.

21. The combination with a railway switch having a plurality of boxes supported on ties and carrying the several rails; of a longitudinal plate secured upon said boxes and abutting the adjacent rails, and a ballast retaining strip carried by said plate and extending to the ties.

22. An article of manufacture comprising a horizontally elongated box comprising a base plate, two side plates and a top plate, said box being adapted to contain operating means for a switch tongue and 85 having its upper portion notched to guide the tongue.

23. An article of manufacture comprising a horizontally elongated box adapted to support switch rails and provided with 90 guiding means for a switch tongue, said box being extensible in length according to the increasing distance between the rails.

24. An article of manufacture comprising a horizontally elongated box adapted to support switch rails and provided with guiding means for a switch tongue, said box being formed of sections adapted to be separated various distances according to the increasing distances between the rails, and 100 means for rigidly securing said sections together in adjusted position.

25. An article of manufacture comprising a horizontally elongated box adapted to support switch rails and provided with guiding means for a switch tongue, said box being formed of sections adapted to be separated varying distances according to the increasing distances between the rails, a separator adapted to be interposed between 105 said sections when the latter are spaced, and means for rigidly securing said sections and separator together.

26. A structure as specified in claim 25, said separator and box sections having interfitting lugs and recesses for the purpose specified.

27. An article of manufacture comprising a longitudinal switch-operating rack bar of stepped formation with teeth on its 120 individual steps.

28. A structure as specified in claim 27, said rack bar being formed of individual sections secured together, each section forming one step of the bar.

In testimony whereof I have hereunto set my hand.

JOHN ALONZO.
